UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

PUSH-BUTTON FOR ELECTRIC SWITCHES.

1,183,076.

Specification of Letters Patent. Patented May 16, 1916.

Application filed November 5, 1913. Serial No. 799,352.

To all whom it may concern:

Be it known that I, CHARLES J. KLEIN, a citizen of the United States, residing at Milwaukee, in the county of Milwaukee and State of Wisconsin, have invented new and useful Improvements in Push-Buttons for Electric Switches, of which the following is a full, clear, concise, and exact description, reference being had to the accompanying drawing, forming a part of this specification.

This invention relates to push-buttons for electric switches.

One of the objects of the invention is to provide improved means for detachably securing extension caps to such push-buttons.

A further object is to provide cap-securing means adapted to compensate for variations in push-button diameters.

20 Further objects and advantages will appear hereinafter.

In order that my invention may be more readily understood, I have illustrated the preferred embodiment thereof in the accompanying drawing, wherein—

Figure 1 is a view of a lamp socket having an elongated push-button, one end of the latter being shown in section; Fig. 2 is an elevation view of a push-button, an extension cap and a securing means, when separated; Fig. 3 is a top perspective of the securing means; and, Fig. 4 is an end view of the same.

The lamp socket 1 incloses a switch mechanism operated by a reciprocable push-button 2. The push-button may be manufactured in a standard length and thereafter readily increased in length when desired by the addition of detachable extension caps 3.

40 The ends of the push-button are of slightly reduced diameter beyond the annular shoulders 4 to receive securing clips 5. The caps 3 are cylindrical in form and closed at their outer ends. If desired, a position indicator 6 for the switch may be fixed to one of the closed ends. The caps are preferably of metal, though they may be made of other suitable material.

50 The clips 5 are designed to fit over the reduced ends of the push-button and to be inclosed by the caps. In order to afford resiliency, the clips are longitudinally split, as at 7. In the preferred form, the opposite ends of the clip are of different diameters and this is effected by providing a

transverse slot 8 in the clip and then permanently contracting the end 9 of the latter to a diameter slightly less than that of the opposite end 10. If desired, an additional slot, 11, may be provided in the portion 10 60 of the clip, for a purpose hereinafter described.

Attachment of the cap 3 to the push-button is readily accomplished by springing the end 9 of the clip onto the button until the 65 same abuts the shoulder 4 of the latter, whereupon the cap may be telescoped over both the parts. The contracted end 9 of the clip thus frictionally grasps the push-button, while the end 10 frictionally engages 70 and is compressed by the interior of the cap. Moreover, the effectiveness of this attachment is enhanced by reason of the cap wedging the resilient arms of the clip against the push-button. In practice, the end 9 of 75 the clip is preferably slightly smaller in diameter than the reduced end of the push-button so that the same may be expanded in use to fit push-buttons of different diameter and accordingly compensate for ordinary variation therein.

In operating the switch, it is apparent that all pressure on the caps is expended in a direction to retain the same on the push-button. If desired, however, a short radial 85 stud 12 may be provided in the cap to enter the slot 11 in the clip and thus hold the parts more rigidly together.

What I claim as new and desire to secure by Letters Patent is:

1. The combination with a lamp socket casing having opposite apertures in its side walls, of an inclosed switch mechanism having a reciprocable operating member with aligned push button extremities protruding through said casing apertures, and a pair of auxiliary extension caps readily attachable to and detachable from said push button extremities for varying the length of said switch operating member, said caps 100 having circuit-indicating push button extremities and including means to telescope on and frictionally engage said first mentioned push button extremities.

2. In combination, a push-button operating member for electric switches, an extension cap adapted to fit over the same, and a resilient split member for securing said parts together, said member having a portion of slightly less diameter than said 110

push-button for receiving the latter and a portion of slightly greater diameter than said cap to be received by the latter.

3. In combination, a push-button operating member for electric switches having a shoulder spaced from its end, an extension cap for said push-button, and a resilient, longitudinally divided clip frictionally interposed between said parts for securing the same together, said clip having one end to be

sprung over said push-button and abut said shoulder and having its other end to be received within and compressed by said cap.

In witness whereof, I have herunto subscribed my name in the presence of two 15 witnesses.

CHARLES J. KLEIN.
